UNITED STATES PATENT OFFICE.

THOMAS F. McMILLIN, OF STREATOR, ILLINOIS.

LIQUID FILTER.

Application filed September 26, 1922. Serial No. 590,740.

To all whom it may concern:

Be it known that I, THOMAS F. McMILLIN, a citizen of the United States, and resident of Streator, in the county of La Salle and State of Illinois, have invented certain new and useful Improvements in Liquid Filters, of which the following is a specification.

My invention relates to liquid filters of the portable type, particularly intended for straining and cleansing milk, and my improvements consist in the provision of a structure that is sanitary in every respect; that may be disassembled quickly and easily for cleaning purposes and as readily reassembled after cleaning; that eliminates the possibility of liquid collecting therein and becoming lost; and that is simple, cheap, extremely durable, and thoroughly reliable and efficient in operation.

With the foregoing and other purposes in view, my invention consists in the novel features of construction, combination and arrangement of parts as will be hereinafter more fully described, illustrated in the accompanying drawings and particularly defined in the appended claims.

In the drawings wherein like characters of reference denote corresponding parts in the different views—

Figure 1 is a longitudinal section of a filter embodying the novel and essential characteristics of my invention;

Figure 2, a fragmentary top plan view; and

Figure 3, a detail of one of the screen sections.

Referring now to the drawings in detail, 10 designates a cylinder formed preferably from a section of seamless metallic tubing and adapted to be supported in horizontal position in any preferred manner as for instance by means of a saddle 11 mounted on a rod or pipe 12 rising from a base block 13, 40 in which event the rod is made rotatably adjustable with respect to either the cylinder or base block or both, whereby the cylinder may be moved conveniently from one position to another as may be desired 45 during its use. Near one of its open ends and in the lowermost portion of the wall thereof said cylinder is provided with a liquid inlet opening 14, while similarly, near its other open end and in the lowermost portion of the wall thereof it is provided with a liquid outlet opening 15, both openings

being provided with suitable sanitary pipe fittings whereby the device may be connected with a source of liquid supply and with a container to receive the liquid after it has 60 passed through the device and been filtered thereby.

A closure 16 in the form of a flanged plug is provided for each end of the cylinder and, as shown, the cylinder ends and the 65 plugs are tapered so that fluid tight joints are provided without the use of gaskets or similar devices when the closures are arranged in closed position. Each closure is pivoted as at 17 to a bar 18 which in turn 70 is pivoted at one end to the cylinder as at 19 while at its other end it is forked to receive a rod 20 which is also pivoted to the cylinder and provided with a screw device 21 whereby said forked end and consequently the plug may be drawn into tight 75 closing engagement with the cylinder, the two pivots 17 and 19 permitting self adjustment of the tapered portions of the plug and cylinder as is apparent.

Adapted to be removably mounted within the cylinder in end to end relation is a plurality of screen supports, three being shown in the present instance and designated respectively at 22, 23 and 24, the 80 first and last being of duplicate construction, but adapted to be arranged in reversed relative relation within the cylinder, while the support 23 is of somewhat different construction and adapted to be disposed between the first mentioned sections in the manner indicated. Each of said supports consists of a pair of relatively spaced rings 85 25 and 26 rigidly connected by rods 27 and in each instance the rings are of substantially the same external diameter as the internal diameter of the cylinder whereby they are 90 slideable therein and have a neat fit. In respect to the support 23 both of the rings are inclined with respect to a horizontal 95 plane as defined by the outer surface of said rings and the latter are disposed relatively in parallelism, while in respect to the supports 22, 24 only one ring is inclined with respect to the horizontal and the other is 100 105 perpendicular thereto. Thus, the three supports may be arranged in end to end relation with their inclined ends or rings disposed adjacent to each other, which results in the perpendicularly disposed rings 110 being located outermost, so as to be engageable with the closures 16 when the latter

are in closed position. The outer faces of both of the inclined rings of support 23 are covered by disks 26' of perforated sheet metal, wire mesh or other foraminous material, while only the inclined rings 25 of supports 22, 24 are similarly covered.

When arranging the screen supports within the cylinder the inclined rings are disposed in downward inclination towards the 10 outlet opening 15, and absorbent cotton 27' or another suitable filtering element is placed between the respective screen supports, while between the cotton and the inclined ring 25 of the support 24 (the one 15 nearest the outlet opening 15) is placed a disk of wire gauze or other small mesh material 28, the purpose of which is to prevent lint from the cotton being carried off with the liquid filtered through the device. 20 With the parts arranged as described closing and fastening of the closures 16 serves to clamp the respective screen supports and filtering elements together in proper relative relation.

25 In operation the milk or other liquid to be filtered enters through opening 14 and passes through the absorbent cotton 27', foraminous disks 26' and the gauze 28 and passes out through opening 15 after all foreign matter has been removed therefrom by the cotton, which latter, because of its inclination due to the inclination of the screen support rings, cooperates with gravity to cause any sediment to collect in the 30 bottom of the cylinder from whence it may be readily removed when the closures are opened and the screen sections and cotton withdrawn for cleaning purposes.

I claim:

40 1. A filter comprising a cylinder having inlet and outlet openings, a closure for each end of said cylinder, a plurality of screen supports arranged within said cylinder and retained therein by said closures, and filtering material disposed between adjacent screen supports, each of said screen supports including a pair of relatively spaced

rings and each of the supports adjacent to the respective closures having one ring disposed at right angles to the axis of said 50 cylinder and the other inclined with respect to said axis.

2. A filter comprising a cylinder having inlet and outlet openings, a closure for each end of said cylinder, a pair of screen supports of duplicate construction within said cylinder one adjacent to each closure, each of said screen supports including a pair of spaced rings the outermost of which is disposed at right angles to the axis of said cylinder and the innermost of which is inclined with respect to said axis, a third screen support arranged between said first mentioned screen support, and filtering material disposed between said third screen support and each of said first mentioned screen supports, said third screen support including a pair of spaced rings each of which is inclined with respect to the axis 60 of said cylinder. 70

3. A filter comprising a cylinder having inlet and outlet openings, a closure for each end of said cylinder, a pair of screen supports of duplicate construction within said cylinder one adjacent to each closure, each 75 of said screen supports including a pair of spaced rings the outermost of which is disposed at right angles to the axis of said cylinder and the innermost of which is inclined with respect to said axis, the inclined 80 rings of the respective supports being disposed in parallelism, a third screen support arranged between said first mentioned screen supports, and filtering material disposed between said third screen support and each 85 of said first mentioned screen supports, said third screen support including a pair of spaced rings each of which is inclined with respect to the axis of said cylinder and disposed in parallelism with the inclined rings 90 of said first screen supports.

In testimony whereof I hereunto affix my signature.

THOMAS F. McMILLIN.
